S. F. Sandborn

UNITED STATES PATENT OFFICE.

SWEN ESKILL SANBORN, OF PHILADELPHIA, PENNSYLVANIA.

EXPLODING TORPEDOES, MINES, &c.

Specification forming part of Letters Patent No. 40,362, dated October 20, 1863.

To all whom it may concern:

Be it known that I, SWEN ESKILL SANBORN, of the city and county of Philadelphia, and State of Pennsylvania, have invented a new and Improved Apparatus for Exploding Torpedoes, Mines, &c.; and I do hereby declare that the following is a full, clear, and exact description of the same, reference being had to the accompanying drawings, forming a part of this specification, in which—

Figure 1 represents a plan or face view of my invention, the cover having been removed to expose the dial and index hand for adjusting the time of the explosion. Fig. 2 is a vertical central section of the case and interior frame-work. Fig. 3 is a plan or top view of the mechanism for adjusting the time of the explosion. Fig. 4 is a plan of the clock-movement and mechanism for setting and releasing the hammer.

Similar letters of reference in the several figures indicate corresponding parts.

The object of this invention is to arrange a hammer, needle, or other equivalent device capable of producing by its action on a percussion-cap, or in any other way, the explosion of a charge of gunpowder, or other other explosive substance or material, in such relation to a clock-movement, or other equivalent mechanism, that the time when the explosion will take place can be adjusted, and that a torpedo, mine, magazine, or any other charge of gunpowder or other explosive material, can be exploded in one, two, or more hours, or minutes or seconds, or at any other moment which may be previously determined.

To enable others skilled in the art to make and use my invention, I will proceed to describe it.

The case F, which incloses the mechanism for exploding the charge, is made of sheet-copper, or any other suitable material, and it is provided with double walls, which inclose an annular space, G, to contain a quantity of gunpowder or other explosive material. The interior of the case is occupied by three circular plates or disks, C D E, which are supported and held apart by studs a b c, as clearly shown in Fig. 2 of the drawings.

H is a small gun or cannons barrel, secured to one of the studs b, between the plates D E. Its muzzle extends through the inner wall of the space F into the annular space G, and its

breech is provided with a nipple, d, to receive an ordinary percussion-cap. The explosion of this cap is effected by the action of a hammer, I, which is secured to a pivot, e, having its bearings in the plates D and E. This pivot is subjected to the action of a coiled spring, which has a tendency to throw the hammer forward to the position shown in red outlines in Fig. 4, and it (the pivot) is made square at its end to receive a suitable key for the purpose of turning the hammer back to the position shown in black outline in the same figure. When the hammer is cocked, it is retained by a trigger, K, which catches over a shoulder, f, on the periphery of a disk, J, that is rigidly secured to the oscillating pivot e. By raising the trigger K the disk J, and with it the hammer I, are released, and by the action of the coiled spring on the pivot e said hammer is thrown with considerable force against the nipple d, thereby causing to explode a percussion-cap on the same, and also the charge of the gun-barrel and of the annular space G. The trigger is raised automatically by the action of a cam, Y, on arbor s, and the time when this takes place is regulated and determined by an ordinary clock-movement, consisting essentially of a balance-wheel, L, escapement M, escapement-wheel N, with its pinion g, which communicates with a spring-wheel, O, by the intermediate gear-wheels, P Q R, and pinions h i j, in the ordinary manner. The wheel O is provided with the usual ratchet-wheel, k, and pawl l, and its arbor m is squared to receive a key for the purpose of winding up the spring. The arbor m', which bears the wheel R and pinion j, is placed in the center of the case, and extends through the plates D and C, and that portion of the same which is situated between said plates bears a pinion, n, (see Fig. 3,) which imparts motion to the train of gear-wheels S o T, also situated between the plates D C. The cog-wheel T is provided with a sleeve-journal fitting loosely on the arbor m', and its hub carries, by frictional gearing, the index-hand or pointer U. (See Fig. 1.) Above the dial-plate C, and firmly connected to this index below said dial-plate, is the disk V, which is provided with a notch, p, in its circumference.

The wheels and pinions which impart motion to the index-hand are so arranged that the same rotates once in twenty-four hours;

but it is obvious that the time can be changed to any desired extent.

In order to release the hammer I automatically at the desired moment, a lever, W, Fig. 3, is attached to a fulcrum-pin, *g*, and made to bear with its end on the periphery of the disk V by the action of a spring, *r*, in such a manner that when the notch *p* in the disk V comes opposite the end of said lever it (the end) drops down into the notch and a partial revolution is imparted to the pin *g*. This pin also carries an arm, *v*, between the plates D and E, and when the lever W bears on the periphery of the disk V, said arm, by coming in contact with the pin *d*, forms a stop for the disk A' and pinion *t*; but if the lever W drops into the notch *p* the arm *v* clears the pin *u*, and the disk A' and pinion *t* are at liberty to rotate. The pinion *t* gears into a cog-wheel Z, on the arbor *s*, which also carries the cam Y, and this arbor is subjected to the action of a coiled spring, which, when wound up, will cause the same to rotate in the direction of the arrow marked near it in Fig. 4. In winding up this spring the arbor *s* has to be turned in the direction opposite to said arrow, and the cam Y will come in the position shown in red outlines in Fig. 4. In this position it is arrested by turning the index-hand and disk V so as to throw the point of the lever W on the periphery of said disk, and the arm *v* in the way of the pin *u*. If the clock-movement is now started, the disk V will revolve in the direction of the arrow marked on it in Fig. 3, and after a certain lapse of time the point of the lever W drops down into the notch *p*, the arm *v* liberates the pin *u*, the arbor *s* rotates in the direction of the arrow marked near it in Fig. 4, and by the action of the cam Y on the trigger *k* the hammer I is released and the charge exploded.

It is obvious that the length of the interval

between the time of starting the clock and the explosion depends entirely upon the length of the arc over which the end of the lever W has to travel until it reaches the notch *p*, and consequently by turning the index-hand more or less the time of the explosion can be regulated.

A stop, *a'*, serves to arrest and to start the clock-movement at any desired time, and a revolving stop, *w*, prevents the arbor *s* from rotating any further than necessary to liberate the hammer I.

This apparatus is particularly intended for the purpose of exploding torpedoes or mines, but it can also be used with advantage on board of a vessel if it becomes necessary to abandon it during an engagement or otherwise, by placing the same in the magazine and adjusting it so that it will do its work either before or after the vessel has fallen into the hands of the enemy.

What I claim as new, and desire to secure by Letters Patent, is—

1. The employment or use for the purpose of exploding torpedoes, &c., of an apparatus, substantially such as herein described, whereby the time when the explosion will take place can be determined and adjusted beforehand with perfect accuracy.

2. The notched disk V, lever W, arm *v*, stop *u*, cam Y, trigger *k*, and hammer I, in combination with a clock-movement constructed and operating in the manner and for the purpose substantially as set forth.

3. The application of the notched disk V to the index hand U, moving on the dial plate C, substantially as and for the purpose specified.

S. E. SANBORN.
